[57] CLAIM

The ornamental design for a vacuum cleaner handle, as shown and described.

DESCRIPTION

FIG. 1 is a perspective view of a vacuum cleaner handle showing our new design;

FIG. 2 is a right side elevational view, the left side elevational view being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

The details shown in broken lines in all view are for illustrative purposes only and form no part of the claimed invention.
